JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

THREAD PARTING AND CLAMPING MECHANISM.

1,279,412.

Specification of Letters Patent. Patented Sept. 17, 1918.

Application filed January 8, 1916. Serial No. 70,838.

To all whom it may concern:

Be it known that I, JONAS NORTHRUP, a citizen of the United States, residing at Hopedale, in the county of Worcester and State of Massachusetts, have invented certain new and useful Improvements in Thread Parting and Clamping Mechanisms; and I do hereby declare the following to be a full, clear, and exact description of the invention, such as will enable others skilled in the art to which it appertains to make and use the same.

The present invention relates to an improvement in thread parting and clamping mechanisms for looms and more particularly, to an improvement in such mechanisms for automatic weft replenishing looms.

When the filling on the bobbin in the active shuttle of an automatic weft replenishing loom has been exhausted to a predetermined extent and the bobbin is about to be ejected from the shuttle so that a new bobbin with a fresh supply of filling may be inserted in its place, mechanism is brought into operation to clamp and part the thread relatively near the shuttle and, thereafter, near the selvage of the cloth.

One object of the present invention is to reorganize the structure of thread parting and thread clamping mechanisms to the end that the parting and clamping of the thread may be more effectively performed than has heretofore been possible. A further object of the invention is to simplify the construction and organization of the thread parting and clamping mechanism in order to render it less liable to derangement by long-continued use and the excessive jars to which such parts are subjected when the loom is in operation.

In accordance with these objects together with others consisting of certain novel features of construction which will hereinafter appear, the advantages of which will be apparent to those skilled in the art, the invention consists in the improved thread parting and clamping mechanism described in the following specification and particularly pointed out in the appended claims.

In the accompanying drawings illustrating the preferred form of the invention, Figure 1 is a view in side elevation of so much of a weft replenishing loom as is necessary to disclose the application of the improved thread parting and clamping mechanism

thereto; Fig. 2 is a view similar to Fig. 1, showing the positions of parts immediately after predetermined exhaustion of the filling has been indicated; Fig. 3 is a view in side elevation showing the positions occupied by the parts of the thread parting and clamping mechanism at the finish of their thread parting and clamping operations; Fig. 4 is a plan of a portion of the filling replenishing end of a loom showing the location of the improved thread parting and clamping mechanism relatively to the shuttle box and to the loom temple; Fig. 5 is a rear elevation of the thread parting and clamping members, and Fig. 6 is a sectional view taken on the line 6—6 of Fig. 5, looking in the direction of the arrow.

The weft replenishing loom to which the improved thread parting and clamping mechanism is applied, may be of any usual or preferred feeler controlled construction. The type of loom illustrated in the drawings comprises a lay 10 supported by a lay sword 11, a breast beam 12, a hopper bracket 13 mounted on the breast beam, and a hopper plate 14 supported by the bracket 13. A hopper arm 15 is fixedly mounted on a rock shaft 16 which extends across the front of the loom and is operatively connected at the other end with the filling feeler mechanism. A shuttle feeler 17 is pivotally mounted at 18 on the hopper plate 14. The hopper arm 15 is articulated with the shuttle feeler 17 through a transferrer arm 19 and a link 20. When the filling feeler mechanism has indicated critical exhaustion of filling in the active shuttle, the hopper arm 15 swings to the right, viewing Fig. 1, and thereby swings the shuttle feeler 17 to the left. The hopper arm 15 is yieldingly connected with the transferrer arm 19 for the purpose of allowing the shuttle feeler 17 to swing forward in case it should contact with the shuttle 21 when the shuttle has not been properly boxed.

The thread parting and clamping members of the improved thread parting and clamping mechanism are located contiguous to each other and are mounted on the lower end of a downwardly and backwardly projecting arm 23 of a bracket 24. The bracket 24 is provided with a forwardly extending arm or shank 25 which is received in a housing 26 mounted on the breast beam 12. A spiral expansion spring 27, the forward end

of which is in engagement with the inner forward wall of the housing 26 and the rear end of which is in engagement with a shoulder on the shank 25 of the bracket 24, tends 5 to maintain the bracket 24 normally at its rearward limit of movement toward the lay. The tension of the spring 27 is such that the bracket 24 and the thread parting and clamping mechanism are maintained practically stationary during the thread parting and clamping operations. The purpose of the spring 27 is to permit the bracket 24 to yield in case the shuttle 21 should strike it when the shuttle fails to be properly boxed. 10 15 20 25 30 35 40 45 50 55 60 65

15 To permit the thread parting and clamping mechanism to be adjusted to accommodate it to different types of looms, a lug 28 projecting upwardly from the housing 26, is secured to an upright 29 of a bracket 30 by a slot and bolt connection. The bracket 30 is fastened to the hopper plate bracket 13. Longitudinal adjustment is afforded the thread parting and clamping mechanism by a slot 31 cut transversely in the upright 29, and vertical adjustment is afforded the mechanism by a slot 32 cut vertically in the lug 28. A bolt 33 secures the mechanism in adjusted position.

30 The thread parting members consist of a longitudinally-movable parting member or plate 35, and an oscillatory parting member 36. The longitudinally-movable parting member 35 is provided with two longitudinally disposed apertures or slots 38 and 39 for the reception, respectively, of a short pin 40 and a long pivot pin 41, which project laterally from the lower extremity of the arm 23 of the bracket 24. The length of the pin 40 is somewhat less than the thickness 40 of the parting member or plate 35. The ends of the slots 38 and 39 limit the forward and rearward movements of the member 35. These slots permit the parting member 35 to move longitudinally, but prevent it from moving laterally. The oscillatory parting member 36 is located immediately adjacent the longitudinally-movable parting member 35, and is mounted on the pivot pin 41. The forward end of the oscillatory parting member 36 is provided with a cam slot 42, through which protrudes a pin 43 projecting laterally from the longitudinally-movable parting member 35. When the pin 43 is moved backwardly toward the lay, its engagement with the upper side of the cam slot 42 swings the oscillatory parting member 36 on the pivot pin 41 until it assumes the open position shown in Fig. 2. A forward movement is imparted to the pin 43 when the rearward end of the parting member 35 is struck by the back plate 45 of the shuttle box 34. This forward movement of the pin 43 engages the lower side of the cam slot 42 and swings the parting member 36 on its pivot in the opposite direction, and there-

by closes it. Rearward movement is imparted to the pin 43 by a bell crank lever 46 pivoted at 47 upon an upwardly extending projection of the bracket 24. The pin 43 is engaged by the rear side of the lower extremity of the vertically disposed arm 48 of the bell crank lever 46. The vertical arm 48 of the lever 46 is moved laterally to actuate the pin 43 when the longitudinally disposed arm 49 of the lever 46 is depressed. The depression of the longitudinal arm 49 of the lever 46 is effected by the engagement of a lug 50 projecting laterally from a bracket arm 51 secured to the upper end of the hopper arm 15, with a lug 52 projecting laterally from the free end of the longitudinal arm 49 when the hopper arm 15 moves to the right upon the indication of critical exhaustion of filling on the bobbin in the active shuttle. The movement of the hopper arm 15 to the right causes the under side of the lug 50 to engage the angularly disposed upper surface of the cam-like lug 52 and ride over it, which depresses the longitudinal arm 49, thereby oscillating the lever 46 on its pivot and swinging the vertical arm 48 to the left. 70 75 80 85 90 95 100 105 110 115 120 125 130

The thread clamping members consist of a stationary clamping member 54 and a pivotal clamping member 55. The stationary clamping member 54 is a thin plate resembling in outline the longitudinally-movable parting member 35 and is sustained in position on the pivot pin 41, which projects through a hole in the member 54, by the engagement of the upper edge of the member 54 with the lower surface of the part 23 of the bracket 24, as shown in Fig. 5. A longitudinal slot 56 is cut in the forward end of the stationary clamping member 54 to provide for free movement therein of the pin 43. The pivotal clamping member 55 is mounted on the pin 41, and its forward end is provided with a cam slot arranged similarly to the cam slot 42 of the oscillatory parting member 36. The cam slot of the pivotal clamping member 55 is engaged by the pin 43 projecting from the longitudinally-movable parting member 35 in the same manner in which the cam slot 42 is engaged by the pin 43. The movement of the pin 43 toward the lay operates to swing the clamping member 55 on its pivot into open position in exactly the same way in which the oscillatory parting member is swung into open position; and the engagement of the back plate 45 of the shuttle box with the rear end of the parting member 35 operates to close the pivotal clamping member 55 in exactly the same manner in which it operates to close the oscillatory parting member 36. 130 135 140 145 150 155 160 165 170 175 180

From the foregoing description, it has been made clear that all the members of the improved thread parting and clamping

mechanism which act directly upon the thread, with the exception of the longitudinally-movable parting member 35, are supported entirely by the pin 41, and that the 5 parting member 35 is supported both by the pivot 41 and by the pin 40. These four members are arranged contiguous to each other and are held in frictional engagement laterally by a properly adjusted spiral 10 spring 58 which encircles the end of the pivot pin 41 projecting beyond the pivotal clamping member 55. The tension exerted by the spring 58 against the thread parting and clamping members is such that, when 15 the vertical arm 48 of the lever 46 pushes the pin 43 toward the lay, thereby moving the parting member 35 to the limit of its rearward travel and swinging the parting member 36 and clamping member 55 into 20 open position, these members remain in this position until the parting member 35 is struck by the back plate 45 of the shuttle box and moved toward the breast beam. When the parting member 35 has been 25 moved toward the breast beam by the engagement of the back plate 45 therewith, and the parting member 36 and clamping member 55 have been swung into closed position, these members remain in this position 30 until the pin 43 is again acted upon by the arm 48. The movement of the pin 43 toward the breast beam oscillates the lever 46 into its normal position. The weight of the longitudinally disposed arm 49 of the 35 bell crank lever 46 is such as to maintain the rear side of the lower extremity of the vertically disposed arm 48 of the lever 46 in constant engagement with the pin 43; but the friction exerted upon the parting 40 and clamping members by the spring 58 is such as to prevent the actuation of the pin 43 by the weight of the arm 49.

When the filling on the bobbin in the active shuttle has been exhausted to a pre-determined extent and this critical exhaustion 45 has been indicated by the filling feeler mechanism,—which operates to rotate the rock shaft 16 and thereby swing the arm 15 to the right,—the engagement of the lug 50 with the lug 52 operates in the manner hereinbefore described to move the parting member 35 toward the lay and to swing the parting member 36 and the clamping member 55 into open position, as shown in 50 Fig. 2. The thread parting and clamping members are now in position for the reception of the filling thread 60, which extends from the fell of the cloth to the shuttle 21, on the next forward beat of the lay. If the 55 shuttle has been properly boxed, by the time the lay has reached its forward center, the back plate 45 of the shuttle box has contacted with the rear end of the longitudinally-movable parting member 35 and has 60 pushed it forward toward the breast beam.

The forward movement of the parting member 35 causes the pin 43 carried by it to engage the lower sides of the cam slots formed in the forward ends of the oscillatory parting member 36 and the pivotal 65 clamping member 55, and thereby swing them about the pivot pin 41 into closed position. The closing of the oscillatory parting member 36 against the parting member 35 parts the thread, and the closing of the pivotal clamping member 55 against the stationary clamping member 44 clamps the 70 parted thread. The thread is then retained between the adjacent sides of the clamping members by their frictional engagement. 75 The construction, arrangement, and mode of operation of the thread parting members and the thread clamping members are such, as clearly appears from the foregoing description, that the thread parting and 80 clamping operations take place substantially simultaneously. Upon the completion of the thread parting and clamping operations, the thread, which has been severed relatively near the boxed shuttle, is held 85 taut by the clamping members, as is shown by the dotted line indicated at 64 in Fig. 4. A thread cutter 61 connected with the loom temple 62 then acts upon the thread to part it at the selvage of the cloth. The parted thread 90 is now held by the clamping members until critical exhaustion of filling in the active shuttle has again been indicated, at which time the pivotal clamping member 55 is 95 swung into open position and thereby releases the thread, allowing it to drop to the floor or into a receptacle provided for the purpose. Fig. 3 shows the position of the parts of the thread parting and clamping mechanism immediately after the completion 100 of the thread parting and clamping operations and before the hopper arm 15 has moved to the left into its normal position. When the hopper arm 15 moves into its normal position, the upper surface of 110 the lug 50 carried by the arm bracket 51 engages the under surface of the lug 52 and raises the longitudinal arm 49 of the bell crank lever 46; and by the time the hopper arm 15 has reached its normal position, the 115 lug 50 has freed itself from engagement with the lug 52; whereupon, the bell crank lever 46 under the influence of the weight of the longitudinal arm 49, swings on its pivot until the rear side of the lower extremity of the vertical arm 48 is in engagement with the pin 43.

It will be observed that when the oscillatory parting member 36 and the pivotal clamping member 55 are in open position, 125 they occupy a low position relatively to the top surface or shuttle race of the lay. In order that these members may not contact with the front top edge of the lay, this portion of the lay is beveled, as shown at 63, so 130

that, when the lay beats up, the pivotally mounted parting and clamping members may slide thereon. The low positioning of the pivotally mounted parting and clamping members relatively to the shuttle race and the beveling of the front top edge of the lay, is to insure the positive engagement of the thread by the parting and clamping members in case the thread should 10 rest upon the shuttle race.

Having thus described a specific embodiment of the invention, what is claimed is:—

1. A weft replenishing loom having, in combination, a lay, a weft replenishing mechanism, and a thread parting and clamping mechanism comprising a longitudinally-movable parting member, an oscillatory parting member located adjacent the longitudinally-movable parting member for co-operation therewith, a stationary clamping member contiguous to the oscillatory parting member, a pivotal clamping member located adjacent the stationary clamping member for co-operation therewith, and a support 25 for the thread parting and clamping members.

2. A loom having, in combination, a lay, a weft replenishing mechanism, and a thread parting and clamping mechanism comprising a longitudinally-movable parting member and an oscillatory parting member co-operating to part the thread, a stationary clamping member and a pivotal clamping member co-operating to clamp the thread, 30 and means for operating the thread parting and clamping members.

3. A loom having, in combination, a lay, a weft replenishing mechanism, and a thread parting device comprising a longitudinally-movable parting member and an oscillatory parting member in engagement therewith, said first parting member having provision for movement in one direction upon an operation of the weft replenishing mechanism 40 to move the oscillatory parting member into open position, and for movement in the opposite direction by engagement with the lay for moving the oscillatory parting member into closed position.

4. A weft replenishing loom having, in combination, a lay, a breast beam, a weft replenishing mechanism including a hopper arm, and a thread parting and clamping mechanism comprising a longitudinally-movable thread parting member, an oscillatory thread parting member and a bell crank lever, said longitudinally-movable parting member having provision for actuation by the bell crank lever to move the oscillatory parting member into open position, and having provision for actuation by the lay for moving the oscillatory member into closed position.

5. A weft replenishing loom having, in combination, a lay, a breast beam, and a

thread parting and clamping mechanism comprising a longitudinally-movable thread parting member, an oscillatory thread parting member, a stationary clamping member, a pivotal clamping member, and means 70 mounted on the breast beam for supporting the thread parting and clamping members, said longitudinally-movable parting member having provision for engagement with the oscillatory parting member and the pivotal clamping member to move them into open and closed positions.

6. A weft replenishing loom having, in combination, a lay, a breast beam, a hopper arm, and a thread parting and clamping 80 mechanism comprising, thread parting members, a stationary clamping member, a pivotally mounted clamping member, and a bell crank lever constructed and arranged for actuation by the hopper arm to actuate 85 the thread parting members in one direction, said parting members having provision for actuation in the opposite direction by the lay, the pivotal thread clamping member having provision whereby, when the 90 thread parting members are actuated by the bell crank lever, it is swung into open position, and when the thread parting members are actuated by the lay, it is swung into closed position. 95

7. A weft replenishing loom having, in combination, a lay, a weft replenishing mechanism including a rock shaft and a hopper arm mounted on the rock shaft, and a thread parting and clamping mechanism comprising, a bracket, thread parting and clamping members mounted on the bracket, and a bell crank lever having provision for engagement with and actuation by the hopper arm upon operation of the weft replenishing mechanism to move the thread parting and clamping members into operative position, one of said parting members having provision for actuation by the lay to move the parting and clamping members 105 into inoperative position.

8. A weft replenishing loom having, in combination, a lay, a breast beam, a weft replenishing mechanism including a hopper arm, and a thread parting and clamping 115 mechanism comprising, a bracket mounted on the breast beam and arranged for movement only when struck by an unboxed shuttle, thread parting and clamping members mounted on the bracket, and a bell crank lever mounted on the bracket adapted to be actuated by the hopper arm to move the thread parting and clamping members into operative position, one of said parting members having provision for actuation by the lay for moving the parting and clamping members into inoperative position. 120

9. A weft replenishing loom having, in combination, a lay, a breast beam, a weft replenishing mechanism including a hopper 130

arm, and a thread parting and clamping mechanism comprising, a bracket yieldingly mounted on the breast beam and thread parting and clamping members, the thread parting members consisting of a longitudinally-movable parting member and an oscillatory parting member, and the thread clamping members consisting of a stationary clamping member and a pivotal clamping member, the longitudinally-movable parting member having provision by virtue of which the oscillatory parting member and the pivotal clamping member are moved into open position upon the operation of the weft replenishing mechanism and are moved into closed position upon engagement of the longitudinally-movable parting member by the lay.

10. A weft replenishing loom having, in combination, a lay, a breast beam, a weft replenishing mechanism including a hopper arm, and a thread parting and clamping mechanism comprising, thread parting and clamping members and a bell crank lever, the thread parting members comprising an oscillatory member and a longitudinally-movable member having provision for actuation by the bell crank lever and by the lay, so that the oscillatory member is moved into open position when the longitudinally-movable member is actuated by the lever and moved into closed position when the longitudinally-movable member is actuated by the lay.

11. A weft replenishing loom having, in combination, a lay, a breast beam, a weft replenishing mechanism including a hopper arm, and a thread parting and clamping mechanism comprising, thread parting members, thread clamping members and a bell crank lever, and connections between the latter and the thread parting and clamping members, said bell crank lever being constructed and arranged to be oscillated in one direction upon operation of the weft replenishing mechanism, and in the opposite direction by the thread parting members upon the forward beat of the lay.

12. A weft replenishing loom having, in combination, a lay, a breast beam, and a thread parting and clamping mechanism comprising, a bracket mounted on the breast beam, thread parting members consisting of a longitudinally-movable parting member and an oscillatory parting member, a stationary clamping member and a pivotal clamping member, said bracket having a laterally projecting pivot pin for supporting the thread parting and clamping members, and said longitudinally-movable parting member having a pin for oscillating the oscillatory parting member and the pivotal clamping member.

13. A weft replenishing loom having, in combination, a lay, a breast beam, and a

thread parting and clamping mechanism comprising, a bracket mounted on the breast beam, thread parting members, thread clamping members, and a bell crank lever, the thread parting members consisting of a longitudinally-movable parting member having a pin and an oscillatory member, and the thread clamping members consisting of a stationary clamping member and a pivotal clamping member, the oscillatory parting member and the pivotal clamping member having cam slots adapted to be engaged by the pin, said pin having provision for actuation in one direction by the bell crank lever and for actuation in the opposite direction by the longitudinally-movable parting member.

14. A weft replenishing loom having, in combination, a lay, a weft replenishing mechanism, and a thread parting and clamping mechanism comprising, thread parting and clamping members, the thread parting members consisting of a longitudinally-movable member and an oscillatory member, the thread clamping members consisting of a stationary member and a pivotal member, said longitudinally-movable member having provision for actuation in one direction upon operation of the weft replenishing mechanism and in the opposite direction by engagement with the lay, said oscillatory parting member and said pivotal clamping member being constructed and arranged to be swung into open position when the longitudinally-movable member is moved in one direction, and to be swung into closed position when the longitudinally-movable member is moved in the opposite direction.

15. A weft replenishing loom having, in combination, a lay, a breast beam, a weft replenishing mechanism including a rock shaft and a hopper arm mounted on the rock shaft, and a thread parting and clamping mechanism comprising, a bracket mounted on the breast beam, thread parting and clamping members, and a bell crank lever mounted on the bracket, said lever having provision for engagement with and actuation by the hopper arm upon the operation of the weft replenishing mechanism to move the thread parting and clamping members into open position, and said parting members having provision for actuation in the opposite direction by engagement with the lay to move the thread parting and clamping members into closed position.

16. A weft replenishing loom having, in combination, a lay, a breast beam, a weft replenishing mechanism including a hopper arm, and a thread parting and clamping mechanism comprising, a bracket mounted on the breast beam and mounted for movement only when struck by an unboxed shuttle, thread parting and clamping members mounted on the bracket and a bell crank

lever, said thread parting and clamping members having provision for actuation into open position by the bell crank lever upon operation of the weft replenishing mechanism, and into closed position by engagement with the lay.

17. A weft replenishing loom having, in combination, a lay, a breast beam, a weft replenishing mechanism, and a thread parting and clamping mechanism comprising, thread parting and clamping members, the thread parting members consisting of a longitudinally-movable member and an oscillatory member, and the clamping members consisting of a stationary member and a pivotal member, the longitudinally-movable member having provision for movement toward the lay to swing the oscillatory member and the pivotal member into open position and having provision for movement toward the breast beam to swing the oscillatory member and the pivotal member into closed position.

18. A weft replenishing loom having, in combination, a lay, a breast beam, and a thread parting and clamping mechanism comprising, thread parting and clamping members, the thread parting members consisting of a longitudinally-movable member including a pin and an oscillatory member, and the thread clamping members consisting of a stationary member and a pivotal member, the oscillatory member and the pivotal member being provided with cam slots adapted to receive the pin and to be actuated thereby into open and closed positions according to the movements of the longitudinally-movable member.

19. A weft replenishing loom having, in combination, a lay, a breast beam, a weft replenishing mechanism including a hopper arm, and a thread parting and clamping mechanism comprising a bracket yieldingly mounted on the breast beam, a bell crank lever pivoted on the bracket, a longitudinally-movable parting member, an oscillatory parting member, a stationary clamping member, and a pivotal clamping member mounted on the bracket, said bell crank lever being normally in engagement with the hopper arm and the longitudinally-movable parting member, and having provision for moving the longitudinally movable parting member toward the lay to thereby open the oscillatory parting member and the pivotal clamping member upon a movement of the hopper arm, said longitudinally-movable parting member having provision for engagement by the lay whereby it is moved toward the breast beam to close the

oscillatory parting member and the pivotal clamping member.

20. A weft replenishing loom having, in combination, a lay, and a thread parting and clamping mechanism comprising, thread parting and clamping members, the parting members consisting of a longitudinally-movable member and an oscillatory member, and the clamping members consisting of a stationary member and a pivotal member, the thread parting and clamping members having provision for actuation into open and closed positions by the longitudinally-movable member, and means for holding the thread parting and clamping members in frictional engagement with each other.

21. A weft replenishing loom having, in combination, a lay, a breast beam, a weft replenishing mechanism, and a thread parting and clamping mechanism comprising, thread parting and clamping members, one of said parting members having provision for longitudinal movement toward the lay to move the thread parting and clamping members into open position, and for longitudinal movement toward the breast beam to move the thread parting and clamping members into closed position, and means having provision for maintaining the thread parting and clamping members in either open or closed position until the longitudinally moving thread parting member is positively engaged to be moved toward either the lay or the breast beam.

22. A weft replenishing mechanism having, in combination, a lay, a breast beam, and a thread parting and clamping mechanism comprising a bracket mounted on the breast beam, a parting member mounted for longitudinal movements on the bracket, an oscillatory parting member coöperating therewith to part the thread, a stationary clamping member on the bracket, and a pivotal clamping member coöperating therewith to clamp the thread.

23. A thread parting and clamping mechanism having, in combination, a longitudinally-movable parting member provided with a pin, an oscillatory parting member engaged by the pin, a stationary clamping member, a pivotal clamping member engaged by the pin, means for moving the longitudinally-movable member in one direction to move the oscillatory and pivotal members into open position, and means for moving said member in the opposite direction to move said members into closed position.

JONAS NORTHRUP.
